LINE LIFT

Application filed April 14, 1930. Serial No. 444,041.

This invention is more particularly intended for use in oil well rigs for the purpose of handling steel wire lines.

Such lines are used for heavy duty such as lifting drill pipe and lowering casing, and extend over a crown sheave at the top of the oil derrick and one end is connected to a spooling drum which is operated by power.

Such lines are connected to raise and lower a traveling block, and one end of the line is connected to a power driven drum and thence runs through a crown head sheave and the traveling block, and the other end is connected to a power driven drum called a calf wheel. There is also installed in the rig a power driven friction pulley called a cathead, the purpose of which is to handle a hemp rope called a cat-line, which is rove through a pulley in the crown head and is adapted to be connected to weighty things or parts that have to be lifted.

The traveling block is very heavy, weighing about one ton, more or less. The raising and lowering of the traveling block is effected by appropriate operation of the drum and the calf wheel, the latter only being used in emergencies. The lines are subject to wear; it often occurring that ten or fifteen lines will be worn out during the drilling of a well, and in order to change the line it is necessary to lower the traveling block to the floor of the derrick, and at other times it becomes necessary to change the sheaves on the crown of the derrick; and when this is required, it is necessary to take the weight of the traveling block and the line, off of the crown sheave that is to be changed.

The line rove back and forth through the sheaves is divided by the traveling block into loops that are called the throws, each of which is carried by a separate sheave in the crown. It is customary to connect the cat-line with parallel limbs of the particular throw which it is desired to free from the crown head sheave that is to be changed, turned or repaired; and heretofore, this connection has been effected by means of a soft rope connected at one end to the cat-line and at the other end, to the opposite limbs of the loop to be lifted.

In practical operation the wire line necessarily becomes covered with oil so that it will move smoothly through the sheaves and it is very difficult to make a stable connection between the cat-line and the limbs of the loop or throw.

Such loops or throws of steel wire line are very heavy and in case the fastening between the cat-line and such loop or throw, slips, the loop falls instantly and with great force; thus endangering life and limb and the safety of the derrick in its descent; and furthermore, in cases where the traveling block has to be raised from the floor, such a slip is likely to be more dangerous because of the falling of the block. The traveling blocks are usually made of very hard castings so that they will wear well; and such castings are so brittle that if the block falls far enough, it will break when it strikes the rotary table of the rig. Such breakage is very expensive as the price of each block runs from one thousand to two thousand dollars, more or less, and the delay of replacing the block causes further expense in time and labor.

An object of this invention is to provide cheap, convenient, simple, easily applied safety means for connecting the cat-line to the limbs of the throw that is to be lifted, or to the line in stringing the blocks; and by my invention it is made convenient and safe to string the line through the block and sheave while the block is on the floor.

Heretofore in stringing the line through the block and the sheaves it was customary to attach the cat-line to the wire line at some distance from the end thereof, and then to operate the cat-line by wrapping it around the friction pulley called the cathead and by operating the cathead to draw the wire line up to the crown sheave, and to string the wire line through the fast sheave, which runs on roller bearings at a high speed. When the wire line end has been passed over the first sheave, and lowered to the floor, it is secured at a considerable distance from its end to the upper end of the traveling block, leaving sufficient length free for stringing through the block sheaves, and over the crown sheaves, after the traveling block has been

raised by operating the drum. Such line is sometimes secured to the traveling block by pieces of soft rope and sometimes by bending the line and securing the limbs of the 5 loop thus made, by what is termed a clamp.

At times the fastenings thus made slip, thus allowing the traveling block and the line to fall to the floor of the derrick with resulting great damage and expense.

10 An object of this invention is to provide means whereby such slipping can be avoided.

My invention is that I provide a lift comprising two metal sleeve segments each having a channel conformed to the twist of the 15 wire line, and I provide a friction cramp yoke adapted to fit onto the sleeve formed by joining the two segments when brought together face to face on the wire line, and connected to the cat-line at one side of the sleeve; 20 and so constructed that when strain of the cat-line is brought onto the friction cramp member or yoke, the sleeve will be clamped friction tight on such line.

Another feature of the invention is the 25 provision of convenient means for making the connection between the cramp member and the cat-line.

Another feature is that I connect the cramp yoke, and the separate sleeve segments, to the cat-line by independent flexible 30 connections, as thin wire cords; the connection for the yoke being of greater length than the other three connections so that when all 35 four flexible connections hang from the same point on the cat-line, the suspended yoke will hang below the lower ends of the sleeve segments ready to be slipped up onto the sleeve segments and into place.

The space between the ends of the yoke 40 arms is sufficient to allow the yoke to be slipped onto the steel line below the segments fitted on such line, and then up the sleeve until the yoke becomes tight on the sleeve; then connection between the cat-line and the 45 ends of the yoke will be made, and the limbs of the cat-line below the lift will be tied together in a well known usual way so that by looping the appropriate limb of the cat-line around the cathead, the operation of the cat- 50 head may be applied to pull the cat-line in one and the other direction to raise or lower the lift, and the wire line to which it is connected.

Other objects, advantages and features of 55 invention may appear from the accompanying drawings, the subjoined detailed description and the appended claims.

The accompanying drawings illustrate the invention.

60 Figure 1 is an elevation showing the newly invented lift in position to lift a throw or loop of line in a derrick which is shown with a calf wheel, a winding drum or spool, with cathead in place and a cat-line suspended over a sheave in the derrick, and applied to

the cathead and to the yokes of the lifts assembled in the derrick for raising and lowering a throw of the wire line, and the traveling block connected to such line.

Fig. 2 is an enlarged perspective detail 70 showing the sleeve segments, and the yoke attached to a wire line, a fragment of which is shown, and also showing the split ring and fragments of the cords which connect the parts to the cat-line. 75

Fig. 3 is a plan view of the sleeve and yoke, omitting the suspending connections shown in Fig. 2; the wire line is shown in place.

Fig. 4 is a side elevation of an assembly of 80 the sleeve segments and the yoke, which latter is shown in section on line x4, Fig. 3; the suspending connections being omitted.

Fig. 5 is an elevation of the twist grooved inner face of one of the sleeve sections.

Fig. 6 is an edge view of the sleeve section 85 shown in Figs. 4 and 5.

Fig. 7 is a view looking up from the bottom of the sleeve formed by the segments fitted together.

Fig. 8 is a view illustrating the position 90 of the lift parts when hung on the cat-line beside the wire line; a fragment of such is shown; and also a sheave and fragments of the cat-line and of the cathead.

Fig. 9 is a fragmental section of the yoke 95 on line x9, Fig. 3, looking toward the ends of the yoke arms.

The oil well derrick 1 with its crown sheaves 2, wire line 3, spooling drum 4, traveling block 5, calf wheel 6, cathead 7, and cat-line 8, are of usual construction and arrangement. Each of the two metal sleeve segments 9, 9', has a twist imprint channel or groove 10 to conform to the twist of the wire line, and adapted to provide for positive anti-slipping 100 engagement of the sleeve when assembled on the wire line.

The cramping yoke 11 may be of cast or wrought steel as a heavy bow 12 provided with forwardly converging limbs 13; and an inner semi-circular downwardly reduced gripping face or seat 14 of more than 180 degrees, adapted to fit the sleeve when the arms 9, 9' are brought together on the line 3, as indicated in Figs. 2 and 4. The yoke 115 arms 13 converge toward each other forwardly from the cramping seat 14 and are spaced apart a distance less than the diameter of the assembled sleeve, and greater than the diameter of the wire line, so that when the sleeve is assembled on the wire line, the yoke may be slipped across the wire line and below the lower end of the sleeve, and may then be drawn up into cramping position on the sleeve as indicated in Fig. 2. 120

The connection for attachment of the cat-line to the yoke arms is provided for by holes 15 in the arms, and an open link 16 having separable hooks 17, 18, pivoted together at 19 and adapted to be passed through said holes 100

side by side to unitedly form means for drawing up the arms of the yoke so as to cramp the sleeve.

The sleeves 9, 9', are provided with ears 20 in which are secured cords 21 by which to attach the sleeves to a ring 22. An ear 23 on the yoke is provided to receive an attaching cord 24 by which the yoke is suspended from said ring 22; and a cord 25 connects the open link 16 to said ring 22, which may be connected to the cat-line 8 at any place therealong desired.

The installation and use of the invention will readily be understood from the foregoing.

The ears 20 are at the tops of the rounded taper outer faces of the sleeve segments, and the ear 23 is at the top of the rear face of the yoke bow for convenient handling of the parts when the cords or other flexible connections are supporting the parts separately.

The concave downwardly reduced gripping face or seat 14 of the yoke is adapted to fit snugly on the taper sleeve to insure ready cramping of the yoke on the sleeve when force upwardly directed relative to the sleeve is applied to the projecting portions of the yoke arms while the sleeve are applied with their twisted grooves on the twisted strand line, and the yoke is on the sleeve.

In practise, to apply the lift to a line, the lift assembly supported by the connections will be swung to the limb of the line that is to be lifted; and if two line limbs are to be lifted, two assemblies will be employed, one for each limb. The workman will first swing the suspended sleeves onto the line on opposite sides thereof and bring them to position where the twist imprints 10, will fit exactly upon the spiral perimeter of the line; then he will swing the yoke into position around the line below the sleeve and will then slip the yoke up the sleeve as far as it will go; he will then attach the split link to the projecting arms of the yoke, meanwhile adjusting the sleeve and yoke to a position where the connections 21 and 24 between the ring and the sleeve segments and the yoke are slack, while the short connection 25 is taut, as shown in Fig. 2; so that an upward movement of the ring 22 caused by the cat-line 8, will move the yoke arms 13 upward to cramp the sleeve segments onto the line. When this is effected, the wire line is under the control of the cat-line and can be lifted as described.

To release the wire line, the cat-line will be slackened, thus lowering the ring, until the weight of the wire line and whatever it carries, has come to rest upon some support; then the yoke will slide down the sleeve and off at the lower end, thus allowing the sleeve segments to swing free from the wire line.

65 I claim:—

1. A line lift comprising tapered sleeve segments adapted to engage a wire line between them; a cramping yoke having a semi-circular seat of more than 180 degrees to embrace and engage said segments, and having arms spaced apart so as to pass a line between them into said seat, and means to move the arms to cramp the yoke seat upon the sleeve segments. 70

2. A line lift comprising sleeve segments having grooves to receive and engage a line between the segments, and to form a sleeve; a cramping yoke on the segments, and a connection by which the yoke may be canted on the sleeve for cramping and clamping the segments thereof onto the sleeve for lifting a line held by the sleeve. 75

3. A line lift comprising a sleeve formed of segments provided on their meeting faces with grooves adapted to frictionally engage a line; a cramping yoke having a seat adapted to fit upon, to hold together, and to frictionally cramp the sleeve and clamp it upon a line, and means to tilt the yoke into cramping position on the sleeve for the purpose of 80 lifting the sleeve and the line. 85

4. A line lift assembly for attachment to a cat-line or the like, comprising sleeve segments having twist face grooves to fit upon a line formed of twisted strands; a yoke adapted to clamp the segments on such line and to frictionally cramp the segments; means for lifting the line connected to the yoke arms for causing the yoke to frictionally cramp upon the sleeve segments; means to suspend the sleeve segments, the yoke and the yoke cramping means from a common support; the yoke suspending means being longer than the other suspending means for suspending the yoke below the lower end of the sleeve segments, for allowing the suspended sleeve segments to be brought onto the line above the level of the suspended yoke; said yoke cramping means being attachable to and detachable from the yoke. 95

5. A line lift assembly comprising a pair of tapered sleeve segments, each segment having on its meeting face a groove provided with twist strand imprints to fit the twist strands of the wire line; each segment being provided on the back of its larger end with a suspending eye; a ring; flexible connections connecting said eye to the ring; a cramping yoke provided at its bow with an eye and having a seat of more than 180 degrees and of less diameter than the larger end of the sleeve formed by the segments and having arms spaced apart to allow the yoke to be passed onto and from the line, and provided with holes; a flexible connection of greater length than either of the sleeve segment connections, connecting the yoke eye to said ring; a split link having hook arms pivoted together and adapted to enter the holes in said yoke arms; a flexible connection for suspending said link 110 115 120 125 130

from said ring with its hooks in position to enter the holes in the arms of the yoke; and a soft line connected to the ring for raising and lowering the same.

5 In testimony whereof, I have hereunto set my hand at Los Angeles, California, this 4th day of April, 1930.

HARRY E. CLARK.
